UNITED STATES PATENT OFFICE.

WILLIAM EUGENE HARTT, OF CONSTANTINE, MICHIGAN.

MOUNTING FOR WASHING-MACHINES.

1,087,232.

Specification of Letters Patent. Patented Feb. 17, 1914.

Application filed February 26, 1912. Serial No. 680,010.

To all whom it may concern:

Be it known that I, WILLIAM E. HARTT, a citizen of the United States, residing at Constantine, in the county of St. Joseph and State of Michigan, have invented certain new and useful Improvements in Mountings for Washing-Machines, of which the following is a specification.

My invention relates to attachments for washing and wringing machines, and the object is to provide attachments by which a washing machine can be swung from one tub to another without detaching the washing machine from the common frame which supports the washing and wringing machines and to provide wringing devices which coöperate with the attachments for swinging the washing machine from one tub to another tub on the opposite side of the frame.

Other objects and advantages will be fully explained in the following description and the invention will be more particularly pointed out in the claims.

The present invention is especially designed as an improvement upon the structure shown in the Flood Patent No. 987,353, dated March 21, 1911, which patent illustrates an arrangement of the type above described.

In order that the invention may be clearly understood, reference is had to the accompanying drawings, forming a part of this specification, and in which—

Figure 1 is a side elevation showing my complete improved washing and wringing machine as it appears when in use; Fig. 2 is a fragmentary, side elevation on an enlarged scale of a part of the wringing machine; Fig. 3 is a front elevation of the apparatus shown in Fig. 1; Fig. 4 is a side elevation of the same, but showing the parts folded into inoperative position; Fig. 5 is an enlarged, detailed side elevation of the washing machine and the improved supporting and shifting means therefor; and Fig. 6 is a detailed view showing a bolt hereinafter described.

Referring to the drawings in detail, the apparatus comprises the usual standards 1, supported upon a suitable base 2, and with which are associated the usual folding brackets 3 and 4, adapted to support the tubs A and B.

The wringing machine, which is designated in its entirety by the reference charac-

ter C, preferably comprises a pair of rollers 5 and 6, urged together by means of adjustable springs 7, which operate in conjunction with horizontally extending arms 8. The usual operating handle 9 is connected with one of the rollers. This wringing machine is permanently mounted in the upper end of the standards 1.

The washing machine is indicated in its entirety by the reference character D, and, as in the Flood patent above mentioned, means are provided whereby such machine can be swung or shifted from one tub to the other. The machine illustrated, comprises a base 10, which may be provided at its ends with adjustable hooks 11, adapted to engage over the edges of the tubs, and thus support the machine. Secured to the base 10 are end frames 12, between which are journaled a large fluted roller 13, and a series of smaller rollers 14 as in the construction usually employed. The roller 13 is mounted upon a shaft 15 to the end of which is secured an operating handle 16. The shaft 15 is journaled in slots 17 in the end frames 12, and outside of such frames is also engaged by notches 19 formed in bearing brackets 18, which are yieldably supported by means of helical springs 20 secured to the base 10. These springs serve to resiliently urge the rollers 13 toward the coöperating rollers 14 in a well known manner.

Pivoted to each end frame 12, as indicated at 20^a, in Fig. 5, is one end of an adjustable arm formed of the slotted sections 21 and 22, secured together by bolts 23, passing through the slots, and preferably provided with wing nuts. The other section 22 of such arm is provided at its end with a nut 24, having at its inner end a flat circular head 24^a, as clearly shown in Fig. 6. This head 24^a is of such size as to just pass through a circular opening 25, which is located at one end of a U-shaped slot 26, in which slot the body of the bolt 24 is adapted to slide. This slot is formed in a U-shaped frame or guide E adapted to be secured directly to the outside of the standards 1, as clearly shown in Figs. 1 and 4, and, to this end, is provided with flanges 27 having holes therein to receive suitable fastening devices.

The essential features of the present invention are illustrated particularly in Fig. 5, and consist of the adjustable arms and the U-shaped guide. In practice, the sections 21

and 22 of the arms are so adjusted that when the washing machine is being shifted from one tub to the other, it will just clear all parts of the wringing machine. During such shifting operation the roller 13 and associated parts are removed from the washing machine so as to permit such machine to turn on the pivot pins 20^a, so that it can be reversed, and the bolts 24 travel in the 10 U-shaped slot of the guide E, passing up one side and down the other. In this way, a much shorter arm suffices to enable the washing machine to clear the wringing machine than would be possible with such arm 15 mounted upon a fixed pivot. Moreover, the guide slot firmly maintains the washing machine in the desired spaced relation from the standards 1, and prevents it from slipping about on the tub. In other words, it 20 will be seen that by the use of my improved U-shaped guide the washing machine is permitted to move freely while being shifted, but is securely maintained in a fixed position when it is once seated upon the tub.

25 What I claim is:—

1. The combination with a supporting

frame, of a pair of inverted U-shaped guides secured to said frame, one at each side thereof, a pair of arms, each having one end connected with one of said guides so as to travel therealong, and a washing machine pivotally secured between the other ends of said arms.

2. The combination with a pair of standards, of a pair of inverted U-shaped guides secured to said standards, a pair of arms each having one end slidably connected with one of said guides so as to travel therealong, and a washing machine mounted between the other ends of said arms, each of said arms comprising a pair of sections adjustably connected, whereby said washing machine is maintained at a fixed distance from said standards, and such distance may be varied, as desired. 45

In testimony whereof, I set my hand in the presence of two witnesses, this 6th day of February 1912.

WILLIAM EUGENE HARTT.
